Primary Examiner — Mehri F Bajoul(74) *Attorney, Agent, or Firm* — Tyler A Stevenson(57) **CLAIM**

I claim the ornamental design for a yard game, as shown and described.

DESCRIPTION

FIG. 1 is a rear, top, left side perspective view of a yard game showing my new design;

FIG. 2 is a rear view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The stippled surface on the back of the yard game form part of the claim. The evenly dashed broken lines circles on the back of the yard game form no part of the claimed design. The dash-dot broken lines illustrate boundary lines and form no part of the claim.
